Primary Examiner — Raphael Barkai(74) *Attorney, Agent, or Firm* — Sterne, Kessler, Goldstein & Fox P.L.C.(57) **CLAIM**

The ornamental design for an adapter for eyewear, as shown and described.

DESCRIPTION

FIG. 1 is a top front perspective view of an adapter for eyewear showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the Figures show portions of the adapter for eyewear that form no part of the claimed design. The dot-dash lines show unclaimed boundaries that form no part of the claimed design.
